SEVERING MECHANISM

Frank L. O. Wadsworth, deceased, late of Pittsburgh, Pa., by Mildred M. Wadsworth, administratrix, Pittsburgh, Pa.; said Wadsworth assignor to Ball Brothers Company, Muncie, Ind., a corporation of Indiana

Original application April 9, 1935, Serial No. 15,416. Divided and this application January 16, 1937, Serial No. 120,925

9 Claims. (Cl. 49—14)

This invention relates to a severing mechanism and more particularly to an improvement in a mechanism for severing individual mold charges from a continuously flowing stream of molten glass, and is a division of a pending application Serial No. 15,416, filed April 9, 1935 by Frank L. O. Wadsworth, deceased and which has matured into Patent No. 2,100,760 of November 30, 1937.

10 The primary object of this invention is to provide a cutting mechanism for severing a continuously flowing stream of molten glass which will be capable of separating the successively formed sections thereof without exerting any retarding action on the flowing material, and which may, if desired, be so operated as to assist the downward movement of the stream at or in the zone of severance.

Another feature of this invention is to provide 20 a cutting mechanism which will shape the severed ends of the stream sections without modifying or interfering with the continuous flow of the molten glass.

A further object of this invention is the provision of a severing mechanism which is adapted 25 to not only perform the last-mentioned function, but which is also adapted to accelerate the downward velocity of the severed charge and to deliver it to the receiving receptacle at a speed that is 30 materially higher than that which it can acquire in a free fall through the same distance, and to further impart to the downwardly moving mass a transverse component of movement in the direction of mold travel. The purposes of these 35 features of improvement are: first—to avoid loss of time in delivery; second—to augment the momentum of the moving charge and thereby increase the compressing effect of its impact on the walls of the mold cavity; and third—to facilitate 40 its delivery to a continuously moving receptacle.

An additional object of the present invention is to provide a form of accelerated delivery shear mechanism which is not only adapted to shape the oncoming lower end of the severed stream to a definite predetermined form, but is also capable of reshaping the upper end of the cut-off section to a different contour from that imparted to it by the cutting operation per se, and to thus obtain a mold charge whose entire cross section, 45 i. e., both the sides and the ends, can be varied and controlled by the accelerated delivery shear mechanism. The utilization of this feature makes it possible to impart to the upper ends of the severed mold charges a substantially flat or, if desired, a concave surface in place of the rounded

or tapered shape obtained by the use of the usual form of severing mechanism, and to thereby eliminate any tendency of the upper end of the charge to lap or fold over on itself when it is deposited in the receiving mold.

Other purposes and advantages of this invention which will hereinafter be made apparent to those skilled in this particular art are accomplished by means of this invention, various exemplary embodiments of which are described in 10 the accompanying specification and illustrated in the accompanying drawings, wherein:

Fig. 21 is a horizontal section of a portion of this mechanism;

Fig. 22 is a plan view of a special form of shear blade and guard cup assembly which is adapted to be used in conjunction with the construction shown in Figs. 17 to 21, inclusive;

Fig. 23 is a vertical cross section on the plane XXIII—XXIII of Fig. 22 with the shear blades closed (as shown in Fig. 17); and

Fig. 24 is another vertical cross section on the plane XXIV—XXIV of Fig. 23.

In the drawings several exemplary forms of shear mechanism are illustrated, any of which may be employed in connection with a forehearth 15 having a glass submerged orifice therein and through which the flow of glass is controlled by any suitable type of continuous forced flow (non-retractive) feeder, to sever the continuously flowing and periodically enlarged stream into a series 20 of mold charges.

The construction illustrated in Figs. 1 to 6, inclusive, comprises a pair of "cat's eye" shear blades 85—85, which are adjustably attached to arms 86—86, that are coaxially mounted in a head 87. One of these arms (86) is secured to, or made integral with, a segmental bevel gear 88, and is provided with a downwardly extending tubular shaft 89 which is journaled in the head 87. The other arm is keyed or clamped to the upper end of a solid shaft 90 which is rotatably mounted in the tubular shaft 89 and in the lower part of the head 87, and which is provided with a second bevel gear segment 91. The two gear segments 88—91 are interconnected by a bevel pinion 92, which is provided with an elongated sleeve hub 93 that is journaled on a fixed stud bolt post 94 carried by the head 87. The rotation of the pinion 92 turns the associated elements 86—88—89 and 86—90—91 in opposite directions about the common axis of the shafts 89—90, and moves the shear blades 85—85 either toward or away from each other.

The head 87 is supported on the upper ends of three parallel links 95—95 and 96, which are 45 respectively engaged by the cross pintle bolt 97 that passes through the lower portion of the head 87, and by the pivot pin 98 in the outer end of a bracket member 99 that is screwed into, and forms a substantially integral part of the tubular 50 stud bolt post 94. The lower ends of the three parallel links (95—95—96) are pivotally attached to a reciprocable cylinder 100, that is slidably mounted on a tubular piston rod 102 that is rigidly clamped in fixed position on the base frame 103. The central points of the three links, 95—95, and 55 96, are respectively coupled to pintle bolt supports 104 and 105 on the base frame (103) by the two pairs of twin arm guide links 106 and 107.

The tubular piston rod 102 carries a fixed pis- 60 ton 108, with relation to which the movable cylinder 100, which surrounds the same, is adapted to slide. The tubular piston rod also carries within its interior a reciprocable piston valve 109 which is provided with two cup-shaped heads 65 110—110 that engage with the end portions of the hollow rod 102, and with an intermediate head 111 that is positioned between the side planes of the piston member 108. The lower halves of the heads 110 are provided with a row of port open- 70 ings 112, which are moved into and out of registry with cooperating ports 114 in the hollow rod 102, by the endwise movement of the valve 109. The tubular rod 102 is also provided with two sets of atmospheric exhaust ports 115—115, which are also opened and closed by the recipro-

cation of the valve member 109, and with radial ports 116—117 which open into the cylinder 100 on each side of the piston head 108.

The port openings 114 are in constant communication with a passageway 118, which is formed in the base plate 103, and which is connected to the casing of a reciprocable piston valve 119 by the pipe 120. The valve member 119 is actuated by a cam 121 which is secured to a cam shaft 121a which also carries the cams controlling the 10 operation of the feeder organization (not shown) and which serves to control the flow of motive fluid from the conduit 65a (connected to a suitable source of supply) to the pipe 120, or its escape therefrom to the atmosphere. In the position of 15 the parts shown in Figs. 1, 2 and 5, the cylinder 100 is at the extreme left hand end of its stroke; the ports 114 at that end of the piston rod 102 are closed; and the adjacent exhaust ports 115 are open. In this position the corresponding supply and exhaust ports 114 and 115 at the opposite (right hand) end of the hollow piston rod, are respectively closed and open, but the pipe 120 is also open to the atmosphere, and both ends of the cylinder 100 are therefore connected, through 20 the ports 116 and 117 with the outside air. When the rotation of the cam 121 permits the valve 119 to be raised—by the pressure in the conduit 65a and also by the return spring 119a—motive fluid will be admitted to the pipe 120 and, through 25 the open ports 112 and 117 to the outer (right-hand) end of the cylinder 100, and will move the latter to the right. This will in turn rock the interconnected link elements 95—106, and 30 96—107 on their pintle bolt supports 104 and 105 35 and will move the head 87 downwardly.

The bevel pinion 92 is provided with a cam block 92a which is journaled on its sleeve hub 93, and is normally held in engagement with a stop block 92b, on the face of the pinion (92), 40 by the spring 92c. As the head 87 is moved downward the cam block 92a is brought into engagement with a fixed cam 125, which is adjustably supported on a vertical post 103a that extends upwardly from the base frame 103; and the engaged elements 92a—92b—92 are rotated in a clockwise direction, on the stud bolt support 94, to move the shear blades 85—85 toward each other and sever the stream of glass flowing from the delivery orifice F of the feeder assembly. It 45 is obvious that this action involves concurrent downward (axial) and transverse (cutting) movements of the shear blades; and that the severing operation will be performed without in any way retarding or interfering with the forced flow of 50 the stream particles when the axial component of shear blade movement—which can be readily controlled by the pressure and rate of admission of the motive fluid in and to the outer end of the cylinder 100—is equal to the velocity of stream 55 flow in the cutting zone. By somewhat increasing the axial speed of shear blade movement—as compared with that of the flowing stream—the severing operation can be made to actually accelerate the downward movement of glass on both 60 sides of the transversely moving blades, and thus assist in shaping the severed ends to a predetermined form or contour.

The shaping action of the downwardly and transversely moving cutting elements (85—85) 70 may be further regulated and controlled by varying the ratio of the concurrent vertical and horizontal movements of the shear blades. This is readily accomplished by changing the form or edge contour of the cam 125. As here illustrated, 75

5 this cam is so shaped that in the preliminary stage of its action the shear blades are rotated through an angle A (from their full open position to the dotted line position of Fig. 2) while the head 87 is moved downward through the distance M (Figs. 6 and 7). This preliminary movement brings the edges of the cutting elements into contact with the surface of the flowing stream. During the succeeding period of severing action the blades 85—85 are rotated through the angle B (to their completely closed position) while the head 87 is moved downward by the additional amount N; but in order to shape the severed end of the flowing stream to an approximately hemispherical contour, (in the plane VII), the initial transverse angular movement B₁ of the shear blades is very slight—as compared to the corresponding axial travel N₁ of the head 87—and is then gradually and rapidly accelerated during the final stage of the cooperative movements B₁ to B₂, and N₁ to N₂.

10 The parts are so proportioned that when the head 87 has reached the end of the movement M+N, the cam block 92a is disengaged from the cam 125; and the shear blades 85—85 are then held in their closed position by the double action spring 127, which has then been moved to the position shown in the lower part of Fig. 6. The 15 downward motion of the head 87 is then rapidly accelerated by the continued movement of the cylinder 100 toward the right, and by the characteristic action of the linkage assembly 95—106 (or 96—107), which is diagrammatically indicated in Fig. 8, where the points 0—1—2' to 8', and 0—1''—2'' to 8'' represent successive correlative positions of the head and cylinder elements 87 and 100. This rapidly accelerated downward movement of the closed shear blades imparts a 20 corresponding velocity to the cut-off charge, which is materially greater than that of free fall;—this increased velocity being, of course, regulated and controlled by the pressure of motive fluid in the right hand end of the cylinder 100.

25 In order to keep the severed charge in alignment with the closed blades 85, 85—and to also prevent any undue flattening of its upper end by the accelerating pressure thereon—a pair of semi-cylindrical guard cups 85a—85a, having hemispherical upper ends, are attached to the shear blade arms 86—86, and are so proportioned as to lightly embrace, but not compress or distort, the sides of the charge and to guide it in its accelerated downward movement.

30 As the moving members approach the end of their outward and downward travel the head of the cylinder 100 engages a pin 100a, which is slidably mounted in the base frame 103, and rocks a lever 100b, which is pivotally supported thereon, to the right; thereby shifting the reciprocable piston valve 109 in the same direction and reversing the port connections 112 and 115 at the opposite ends of the hollow piston rod 102. This 35 opens the right hand end of the cylinder to the atmosphere and puts the opposite end thereof in communication with the motive fluid pipe and passage 129—118; thus first cushioning, then arresting, and finally reversing the movements of the parts 87—95—100, etc. Since the terminal velocity of the downwardly moving parts 85—85a—87, etc. is high, and these parts have considerable mass, it is desirable to assist the cushioning and reversal of the downward movement by the use of highly elastic springs 103b—103c which are adapted to engage the lower ends of

the head and cup members 87 and 85a at the lower end of their travel.

40 In order to open the connected shear blade and guard elements 85—85a before the downward movement is completed—and thus completely release the mold charge from any decelerating restraint on its continued fall under the velocity already imparted to it—a tapered finger 128 is provided, which is adjustably mounted in the base plate 103, and which is adapted to enter a notch 130, in the overlapping edges of the shear blade arms 86—86, and force them apart until the double acting spring 127 passes the dead center point; after which this spring acts to complete the opening movement. The released 45 charge is then permitted to move on downward through the coil 103b and through an opening in the base plate 103, and is projected into the receiving receptacle therebeneath at the maximum velocity imparted to it by the above described action of the accelerated delivery severing mechanism.

50 In the return upward movement of the parts 87—95—106 etc. the valve 119 is held in its raised position during the first part of the travel of the cylinder 100 to the left; and is then moved downward until it closes the opening to the pipe 128, and thus traps the already admitted motive fluid in the left hand end of the cylinder and in the connected passage and pipe chambers 118—20. 55 The completion of the return movement to initial position is accomplished by the expansion of this trapped fluid; and at the end of this movement the projecting boss on the left hand cylinder head engages an outwardly projecting lug 109c on the valve head 110, and moves the valve 109 to the position shown in Fig. 5. This again opens communication between the pipe 120 and the right hand end of the cylinder 100, but the amount of residual fluid remaining in the passage 118 and 60 the pipe 120 is now so small that it will not exert any material actuating pressure on this end; and if desired the cam 121 may be so shaped that the valve 119 is depressed and the pipe 120 thus opened to the atmosphere as soon as the 65 valve 109 is moved to the left. The expanded fluid in the inner end of the cylinder chamber (100) is partially trapped therein, by the covering of the adjacent piston rod port 115 by the overlying hub of the cylinder head, and serves 70 to hold the shear head 87 and its associated parts in their initial elevated position, until the cam 121 permits the valve 119 to be again raised and reopen the connection to the motive fluid conduit 65a.

75 In the return upward movement of the shear head 87 the pivoted cam block 92a is engaged by the lower end of the cam 125 and is rocked in a counterclockwise direction on the gear hub 93 until it passes the said cam, and is lifted above 80 it; after which it is returned to normal engagement with the gear lug 92b by the spring 92c. This completes the cycle of severing and of accelerated delivery action.

85 It is sometimes desirable to impart to the severed and downwardly projected mold charge a lateral or transverse component of movement in the direction of mold travel, so as to facilitate the delivery of the charge to the receiving receptacle while the latter is in motion. This is 90 most effectively accomplished in this improved delivery mechanism by shifting the position of the pintle bolt supports 104 and 105 for the guide link arms 95 and 96. When the centers of these pintle bolts are at the intersection of the vertical 95

and horizontal lines through the pivot connections at the ends of the links 95 and 96 the head 87 moves parallel to itself along the vertical line 97, 104. When these centers are shifted inwardly 5 to shorten the guide arms 106 and 107—e. g., when the pivot bolt support 104 is moved to the position C of Fig. 9—the head member 87 will still move parallel to itself but will travel along the curved line 97—a—d. When the pivot bolt 10 centers are moved outwardly and the link arms 106 and 107 are correspondingly lengthened—e. g., when the pivot bolt 104 is moved to the position D of Fig. 9—the travel of the head 87 will be along the curved line 97 a'—d'. The 15 downward movement of the shear blade elements 87—85—85a in the curved path, 97—d or 97—d', will impart to the severed charge a horizontal component of velocity, V or V', which will be controlled by the amount of shift of the pintle 20 bolt supports 104 and 105, and which can be directed to the right or the left along the line of travel of the receiving receptacles—in the plane III—III of Fig. 2—so as to eliminate any relative lateral movement of the downwardly projected 25 charge with respect to the horizontally moving mold.

The result last described can also be obtained by shifting the points of connection between the outer ends of the guide arms 106 and 107 and 30 the associated parallel links 95—95 and 96. If, for example, the connection between the arms 106 and the links 95 is moved from the point E to the point G (see Fig. 10) the path of travel of the shear blade assembly is changed from the 35 straight line movement 97—104 to the curved line movement 97—a'—e'. By shifting the point E in the opposite direction the path of travel of the head will, of course, be inclined to the left by a corresponding amount.

40 Figs. 11, 12 and 13 illustrate another embodiment of my improved shear mechanism. In this construction the parts 85b—86a—83a—89a—90a and 91a correspond in all material respects with the correspondingly numbered elements of the 45 previously described assembly (see Figs. 3 and 4), and do not, therefore, require further description. The head 87a on which these parts are mounted is of an open box shaped form, and is provided on one side with a stud shaft support 50 94a which carries the bevel pinion 92d that serves to interconnect the upper and lower bevel gear segments 88a and 91a and to concurrently rotate the shear blade arms 86a—86a in opposite directions around the axes of the concentric shafts 55 89a—90a.

The shaft 90a projects for some distance beyond the top and bottom faces of the box shaped head 87a and is slidably mounted in the projecting arms of a U-shaped bracket 133, that is secured to an adjacent portion of the forehearth boot (10). The bifurcated vertical leg of this bracket (133) carries a cross shaft 134 which is connected to, and revolves at the same speed as the cam shaft 121a of the feeder assembly, 60 and which is provided with a cam 125a that is adapted to engage, at suitable intervals, with a cam roller 92e on the bevel pinion 92d and thereby move the shear blades 85b—85b toward each other. The shaft 134 is also provided with a second cam 135 which is positioned between the inner faces of the bifurcated bracket 133, and is adapted to engage a cam roller 136 that is 65 rotatably mounted between the twin arms of a bell crank lever 137. This lever (137) is pivotally mounted on the bracket 133 and is en-

gaged at its outer end with the upper face of the shear head 87a.

The operation of this last described mechanism is as follows: When the parts are at rest, the shear head 87a is normally held in its raised position by the tension spring 138; and the shear blades 85b—85b are held open by the two way spring 127a. During this period of inactivity or rest, the axis of the spring 127a and the center of the cam roller 92e occupy the dotted line positions H' and H of Fig. 11. When the rotation of the shaft 134 brings the advancing edge of the cam lobe 125a into engagement with the cam roller 92e the pinion 92d is revolved through the angle H—J, and the shear blade arms are correspondingly moved toward each other through the angles A—A' (see Fig. 12). This rotary movement brings the edges of the cutting elements into close proximity to the surface of the flowing stream of glass; and the cam 135 then comes 20 into action to rock the bell crank lever 137 on its pivot support and initiate the downward movement of the head 87a (and its associated parts) on its shaft bearings in the bracket 133. This downward movement cooperates with the continued rotation of the cam 125a in effecting a further rotation of the bevel pinion 92d through the angle J—K, and completing the closing movement of the shear blades;—the ratio between the axial and the transverse (cutting) motion of the severing elements being controlled and determined by the edge contours and the phase relationships of the two cams 125a and 30 135. As shown in Fig. 14 (diagram) the arrangement is preferably such that the final angular 35 movement through the arc J—K is progressively accelerated with respect to the concurrent downward movement through the distance O—N, (as indicated by the successive coincident positions J—O, J₁—O₁, J₂—O₂, K—N), so as to 40 shape the severed end to such a form as is shown in Fig. 7; but it is apparent that the arrangement may be varied so as to obtain any desired relationship between the concurrent axial and lateral movement of the cutting edges. 45

As soon as the downward movement of the head 87a has carried the cam wheel 92e below the path of action of the cam 125a (at point N of Fig. 14) the angular movement of the bevel gears and shear arms is arrested, and the shear blades are held in their closed position by the two way spring 127a whose axis has now passed the dead center position of Fig. 11 and occupies the dotted line position K'. The downward movement of the head 87a, and of its associated parts, continues under the action of the cam 135—preferably at a somewhat accelerated speed—until the closed shear blades have been carried away from the oncoming end of the severed stream, and the bevel pinion 92d is then 60 rotated in the reverse (clockwise) direction by the engagement of the gear lug 127b (to which the outer end of the two-way spring 127a is pivotally attached) with an adjustable post 128a that is bolted to the lower arm of the U-shaped frame 133. This opens the shear blades, and as soon as this occurs the continued rotation of the shaft 134 moves the raised lobe of the cam 135 out of engagement with the cam roller 136 and the head 87a is then returned to its 70 initial raised position by the spring 138.

In order to prevent any rotation of the reciprocable member (87a) under the edge thrust of the revolving cam 125a, and to also assist in maintaining the desired alignment between the 75

axis of the stream and the centers of the guard cups 85c—85d, the head (87a) is provided with a laterally extending arm 87c whose outer end is slidably engaged between the inner faces of the bifurcated bracket support 133. The downward movement of the head, under the action of the cam 135, may, if desired, be effected by the direct engagement of that revolving member with this guide arm (87c); but it is preferred to use the pivoted bell crank element 137 for this purpose because it permits of the use of a cam member of smaller diameter, and also affords another means of changing the ratio between the axial and the transverse movements of the shear blade elements. From the foregoing description it is apparent that this improved shear mechanism (e. g. Fig. 11) is designed to carry out a procedure in which at least some portion of the charge shaping operation is accomplished by predeterminedly controlling the application of the severing forces transversely of the elongated mass or flowing stream, while at the same time varying in a predetermined relationship, the point of application of the forces longitudinally of the mass. Stated differently, the shaping of the lower end of each charge is effected by controlling the transverse movement of the shear blades and their axial movement relatively to the particles of the mass subjected to the severing forces.

In the form of construction shown in Figs. 11, 12 and 13 only a slight initial acceleration is given to the cut-off charge, because of the limited range of downward movement beyond the plane of shear blade closure. But this movement can be continued to any extent desired by the use of the modified form of construction shown in Fig. 15, in which the head 87d—(that is in all essential respects the same as the one shown in the three preceding figures)—is movably supported on a triple parallel link assemblage (95a—96a) like that previously described. In this case the shaft 134a is provided with a third cam which controls the movements of a "timer" valve 119b that controls the flow of motive fluid to the actuating cylinder of the parallel link assembly; and this cam is so set that motive fluid is admitted to the pipe 120a, (which corresponds to the pipe 120 of Figs. 1, 1a, 2 and 5) just before the lever 137a ceases to act. The downward movement of the head 87d, which has been controlled during the severing operation by the lever 137a (in the manner already explained), is then continued by the action of the parallel link system (as described in connection with the construction of Figs. 1 to 4, inclusive) until the desired acceleration (and lateral velocity) has been imparted to the cut-off charge; and the head 87d and its associated parts are then brought back to initial position by the return movement of the link system.

In the construction shown in Figs. 16 to 24, inclusive, each pair of cooperating shear blade and guard cup elements 85c—85d is reciprocably mounted as a unit, on the short leg of an L-shaped arm 140 which is pivotally supported by a vertical pintle bolt 141 that passes through an elongated hub 142 at the inner end of the arm 140 and is rigidly secured in the head 87e. The arms 140 are normally held apart—in the open position indicated by dotted lines in Fig. 20—by a twin coil spiral spring 144 which passes around the lower ends of the hub members 142 and whose extremities are attached to intermediate points of the arms (see Fig. 21); and said arms are moved symmetrically toward each

other—to the closed position shown in Figs. 16 to 24, inclusive—by two cams 145—145 which are attached to the revolving shaft 134b and which are adapted to engage with cam rollers 147—147 that are journaled on stud bolt supports 148—148 on the hubs 142—142.

Each shear blade is provided with a curved cutting edge (see Fig. 16) and is adjustably secured to the upper end of the associated guard cup 85d which is provided on one side with a V-shaped gib that slides in suitable guideways 153 on the contiguous face of the arm 140 and which is also provided with a lug 150 that projects through a slot 151 therein; and this lug is flexibly coupled—by a pin and slot connection—to the outer end of a twin arm bell crank lever 152 that is pivotally mounted on the head of the stud bolt 146. Each of these bell crank levers is provided with a cam roller 153 which is journaled in the short arm thereof, and which is adapted to be engaged, at suitable intervals, by a single lobed cam 125b that is also secured to the shaft 134b. During the periods when these elements 153 and 125b are out of engagement, the interconnected members 85d and 152 are held at the outer limits of their oscillatory or reciprocatory movements by the compression springs 154 that are interposed between the L-shaped arms 140 and the bifurcated levers 152.

The head 87e, which carries the parts 140—152 etc., is movably supported on three "parallel links" 95b, 96b—96b, whose inner ends are pivotally connected to the head 87e and whose opposite or outer ends are coupled to a pair of rocking guide arms 155—155 which are journaled on a rigid frame 156 that is adjustably supported in any suitable manner (e. g. by the posts 157) on the forehearth boot; and which are themselves connected—e. g. by the bar 158—so as to move in synchronism and in parallelism with each other. The frame 156 carries a cylinder 160 which is provided with a reciprocable piston rod member 161 whose outer end terminates in a cross head 162 that slides in suitable guideways on the frame; and this cross head is connected, by the connecting rods 163 to the upper ends of a pair of bell crank levers 164 which are keyed to a cross shaft 165 that is journaled in an adjustable block 166 secured to the frame 156. The lever members 164 are also cross connected by the spacing bolt collars 167; and their outer ends are pivotally coupled to the parallel link elements 95b—96b by the trunnion-spacer-bolt 168. The two links 96b are rigidly cross connected by the spacer collars and bolts 170 and by an inverted T-shaped bar 171 whose central upwardly projecting stem is positioned between the adjacent faces of the cams 145—145, and which carries a pair of rollers 172 that are adapted to be engaged by the edges of the associated cam elements 135a—135b.

The admission and exhaust of motive fluid, to and from the opposite ends of the cylinder 160 is controlled by a balanced double piston valve 173 (see particularly Fig. 18), which is moved in one direction (to establish communication between the motive fluid conduit 174 and the inner, left-hand end of the cylinder 160) by a central cam 175 on the shaft 134b; and in the other direction—(to connect this conduit with the outer, right-hand end of the said cylinder)—by the conical coil compression spring 176.

The shaft 134b (like the shaft 134 of Fig. 11) is revolved in synchronism with, and at the same speed as, the cam shaft 121a of the feeder organ.

ization; and the cycle of operation of the last described mechanism is as follows:

When the desired quantity of glass has been expelled from the delivery orifice (F) of the feeder, the cams 145 engage the cam rollers 147 on the arms 140 and move the latter to the closed position shown in Figs. 16 and 20, where they are held in locked engagement with each other by the dowel pin 177 and the spring pressed latch 178. This movement brings the cam rollers 153 into the plane of action of the cams 125b; and at the conclusion of the said movement the advancing edges of the rotating elements 125b engage the rollers 153 and begin to rock the levers 152 on their trunnion supports on the stud bolt heads 148. During the first phase of this action, (i. e. during the closing movement of the arms 140), the head has been held in its elevated position—with the rollers 172 in engagement with the depressed, or reduced diameter portions of the cams 135a)—by the pressure of motive fluid in the outer end of the cylinder 160; but as the cams 125b engage the rollers 153 the cam 175 begins to move the valve 173 to the right, thus opening communication between this end of the cylinder and the atmosphere, (see Fig. 18); and the interconnected head and link elements are then moved downwardly by the action of the cams 135a on the rollers 172. This downward motion of the head 87e cooperates with the rotary motion of the cams 125b in producing a concurrent axial and transverse movement of the shear blades, 85c, with and through the molten material—(the ratio between these concurrent movements being determined and controlled by the edge contours and phase relationships of the cams 125b and 135a)—and correspondingly shapes the oncoming severed end of the flowing glass to any desired and predetermined form.

It may be noted that in the operation of the construction now under consideration the closing (i. e. cutting) movement of each shear blade (85c) is effected and controlled by its own actuated cam (125b); and that in consequence of this, the ratio between the axial and the transverse travel of each of these elements may be independently varied, (by changing the edge contour of the corresponding cam), so as to obtain, if desired, an unsymmetrical severing and shaping of the two sides of the flowing stream—(e. g. one-half of the severed end may be tapered or rounded more or less than the opposite half)—and thus compensate for slight inequalities in temperature and in velocity of flow in different parts of the molten material as it is expelled from the delivery orifice.

When the shear blades have been brought to their closed position, by the concurrent lineal and rotative movements of the head 87e, and the cams 125b, the rollers 153 pass out of the range of action of the cams 125b, and the associated shear blade and guard cup elements, 85c—85d, are locked to the arms 145—145 by the spring actuated latches 180—180. In the meantime the continued rotation of the cam shaft 134b during this second stage of the operation—(i. e. during the severance of the flowing stream)—moves the valve 173 to its full line position in Fig. 17 (and dotted line position of Fig. 18) and thus places the inner end of the cylinder 160 in communication with the motive fluid conduit 174. The downward movement of the head 87e which has been initiated, and up to this time controlled, by the cams 135a, is then continued, at a progressively increased speed, by the outward move-

ment of the piston-piston-rod elements 161—162, and the resultant clockwise rotation of the bell crank levers 164; and the severed stream section, that is now embraced by the closed shear blade and guard cup elements 85c—85d, is projected downwardly at an accelerated velocity, which is controlled by the pressure in the cylinder, and which is preferably materially greater than that imparted to it by gravity action alone (infra).

When the desired speed of delivery to the receiving receptacle (e. g. the forming mold) has been attained, the levers 152 and the arms 140 are concurrently released from their interlocked relationship by the engagement of a tapered, or wedge shaped finger 128b with the latches 178 and 180; and the parts are returned to their fully separated or open positions (see dotted lines of Fig. 20), by the springs 144 and 154. The valve 173 is then moved to the left by the rotation of the cam 175 and the action of the follower spring 176, thus placing the outer end of the cylinder 160 in communication with the motive fluid conduit 174 and opening the opposite inner end thereof to the atmosphere. The link supported head 87e is immediately lifted to its initial position, and held in that position, by the pressure of the motive fluid on the outer side of the piston element 161, in readiness for a repetition of the above described cycle of operation.

The line of movement of the head 87e is controlled by the positioning of the trunnion shaft support 165 for the bell crank lever 164. When this support is located at the point shown in Fig. 17, the point of connection between the lever and link elements 164—96b travels in the arc of a circle 168f, and the head 87e will correspondingly move along the substantially straight vertical line O—f'. When the trunnion support is lowered (e. g. to the point P) the pivot bolt 170 will travel in the arc of a circle 168p, and the path of movement of the head will then be inclined outwardly (as indicated by the dotted line O—p). If the pivotal axis of the lever 164 is raised (e. g. to the point R) the pivot connection 163 will move in the arm of a circle 168r; and the movement of the head (87e) will be along the inwardly inclined path O—r (see Fig. 17). In both cases the degree of inclination of the paths O—p or O—r will be dependent upon the amount of shift of the bell crank support 165—166; and by adjusting this up or down the lateral component of movement of the downwardly projected charge—to the left or right of the vertical—can be varied and controlled, to impart to the said charge a horizontal velocity which corresponds to that of the moving mold into which it is projected.

The use of the accelerated delivery shear mechanism also enables the reshaping of the upper end of the cut-off stream section to various forms, which are materially different from that which is produced by the cutting action per se. This reshaping effect is obtained by utilizing the accelerating pressure, or downward thrust,—which is exerted by the closed shear blades, on the mass of soft plastic glass that is embraced by the closed guard cups 85d—to spread or expand the upper end of the cut-off charge until it completely fills the adjacent portion of the guard cup cavity, and assumes whatever cross sectional form or outline that may be given thereto (see, for example, Figs. 7, 17, 23 and 24). If this upper end of the severed section is to be of convex or flattened contour (see Figs. 7 and 17), the shear blades 85c may be of the usual "cat's eye", or concaved edge

form shown in Fig. 2 or 16—because in those cases the meeting edges of the cutting elements may be permitted to overlap each other to any desired extent;—but when the re-shaped end is to be given a concaved outline (as shown in Figs. 23 and 24) the edges of the reversely surfaced shear blades must be straight (as shown in Fig. 22) and can only be allowed to overlap the small distance required to ensure a clean complete severance of the flowing stream of viscous material.

It will also be apparent that the above described re-shaping action may be employed in the formation of mold charges which are of a conical or frusto-conical form (as indicated by the dotted lines of Figs. 23 and 24)—and which may have either a circular, or an oval, or an egg-shaped cross section—by correspondingly shaping the interior surfaces of the guard cups 85a—85d, and by moving these elements downward at such a speed as to obtain the necessary accelerating and spreading pressure on the upper ends of the cut-off sections of molten material. When the closed shear blade and cup elements are opened—25 by the action of the fingers 128—128a or 128b—the re-shaped charge is completely released and continues to move downward, in the direction, and at the maximum velocity, previously imparted to it by these elements.

80 It is desirable to eliminate, as far as possible, any cooling of the external surface of the re-shaped mass by the enclosing faces of the guard cups, and the latter are for this reason highly polished and may, if desired, be chromium plated.

35 The time of contact between the shear blades and guard cup elements and the glass is of course exceedingly short, and the attendant transfer of heat from the semi-molten material to the cooler metal is correspondingly small; but in 40 order to avoid any possible overheating of the latter, a pair of nozzles 182—182 are provided (see Figs. 17 and 20), which are positioned outside of the path of movement of the members 85c—85d, but in such relation thereto, that when these 45 parts are in their opened and raised position they are exposed to blasts of cooling fluid which issue from these nozzles and are directed against the lower and inner surfaces of the shear blades and cups. The fluid which is used is preferably one 50 which will not only exercise the desired cooling effect, but will also deposit a thin film of lubricant (e. g. water or oil vapor) on the glass engaging surfaces, and will thereby eliminate any tendency to either mar the mold charge "skin" or to cause 55 to adhere to the hot metal.

Because of the high reciprocatory speed at which the elements of the accelerated delivery (and charge-re-shaping) mechanism are preferably operated; it is desirable to minimize the effects of inertia and momentum, by keeping all of the rapidly moving members as light as possible; and with this object in view it is preferred to make the majority of such parts of either aluminum, or stainless (18—8) steel, or of suitable aluminum alloys, which have the additional characteristics of being relatively insensitive to thermal distortion at high temperatures. It will, of course, be understood that in the case of such constructions as are shown in Figs. 15 to 24, inclusive, recoil springs—such as are illustrated in Fig. 1—may be employed, if desired, to assist in elastically checking and reversing the downward movement of the shear head, after the shear blade and guard cup elements have been opened to release the moving charge. It will also be under-

stood that various structural details of the several form of apparatus hereinbefore disclosed (but which have not in all instances been specifically illustrated or described) can be readily added or modified by the skilled draftsman or machinist without further explanation.

From the foregoing it is apparent that with the present invention the severance is effected in such a way that it does not retard or interfere with the unrestrained downward movement 10 of the stream particles, either in, above, or below the plane of severance, but the mechanism, on the contrary, may be so operated that it will actually assist this downward movement.

It will also be apparent, to those skilled in this art, that the above described accelerated delivery shear mechanism—which severs the continuously flowing stream without retarding or interfering with its free downward movement in the zone of severance, and which imparts to the 20 cut-off section a velocity that is materially greater than it can attain under the action of gravity alone—affords a very efficient means of supplying a rapid succession of preformed mold charges to the receiving receptacles of a forming machine, and thereby materially increases the possible speed of operation, and the resultant output, of the said machine. It will also be apparent that these results can be accomplished by combining the accelerated delivery (and 30 charge re-shaping) shear mechanisms heretofore described with any type of continuous forced flow feeder construction; and that, with the preceding disclosure as a guide, engineers or others familiar with glass fabricating operations, 35 will be enabled to design many other alternative forms of apparatus which will embody in whole or in part the characteristic features of the present invention.

It is to be understood that various other 40 shear structures and shearing procedures for severing a continuously flowing stream of molten glass to produce mold charges, and in which the shear blades move downwardly with the stream but which structurally and functionally 45 distinguish from the features herein claimed, have been devised by this inventor and that such mechanisms and procedures form the subject matter of and are claimed in pending applications for patent, and that the novel subject matter 50 disclosed but not claimed herein is claimed in the following identified patents: No. 2,092,865 of Sept. 14, 1937, No. 2,108,518 of Feb. 15, 1938, No. 2,100,760 of Nov. 30, 1937, and 2,090,082 of August 17, 1937.

55 What is claimed as new and desired to be secured by Letters Patent is:

1. A shear comprising a vertically movable frame, a spring for yieldingly holding said frame in its upper position, shear blades mounted on 60 said frame, means for moving said blades laterally to close the same, a cam for actuating said blade closing means, a bell crank lever for lowering said frame and imparting an axial movement to said blades, and a cam for actuating 65 said bell crank lever, said cams being arranged to maintain a desired relationship between the axial and lateral movement of said blades.

2. A shear comprising a vertically movable 70 frame, shear blades mounted on said frame, means for moving said blades laterally to close the same, a cam for actuating said blade closing means, a two-way spring associated with said blades for holding the blades in both their open 75

and closed positions, a bell crank lever for lowering said frame and imparting an axial movement to said blades, a cam for actuating said bell crank lever, said cams being arranged to maintain a desired relationship between the axial and lateral movement of the blades, and means for actuating said spring to open said blades at the end of the downward movement of the frame.

3. A mechanism for severing a stream of molten glass comprising a head, parallel pivoted links for supporting said head, arms pivoted on said head, a shear blade slidably mounted on each said arm, means for closing said arms, means for locking said arms in their closed position, means for moving each said blade relative to its arm to close the same, means for swinging said links to move said head downwardly simultaneously with the closing of said blades, and means for releasing said arm locking means.

4. A mechanism for severing a stream of molten glass comprising a head, a parallel pivoted linkage supporting said head, arms pivoted on said head, a shear blade reciprocably mounted on each said arm, means for closing said arms, means for moving said blades relative to said arms to close the same, and means for swinging said parallel linkage to lower said head simultaneously with the closing of the blades.

5. In combination with means for periodically severing mold charges from a suspended stream of molten glass, means for enclosing the charges so severed, means for moving said severing and enclosing means downwardly with said severed charges at a greater speed than the speed of the natural gravity fall of said charges, stationary means for opening said severing means as it approaches the limit of its downward movements and spring means in the path of movement of said enclosing means for assisting in cushioning and reversing the downward movement of said severing and enclosing means.

6. The combination with means for periodically severing mold charges from a suspended stream of molten glass and enclosing said charges, of mechanism for moving said means downwardly with said severed charges at a greater speed than that of the normal gravity fall of said charges, stationary means for releasing said charges as said means approaches the limit of

its downward movement, a stationary coiled spring in the path of movement of said means for assisting the cushioning and reversal of its downward movement and through which the severed charges pass on their way to receiving molds.

7. In a shear mechanism, a support member, a pair of oppositely movable shear blades mounted on said support member, charge enclosing means carried by said shear blades, means for closing said blades and said charge enclosing means, elastic fluid operated linkage mechanism for causing said blades to periodically sever mold charges from a suspended stream of molten glass and moving the same downwardly, means for opening said shear blades and said mold charge enclosing means as they approach the limit of their downward movements and spring means in the path of movement of said enclosing means for assisting in cushioning and reversing the same.

8. The combination of means for periodically severing mold charges from a suspended stream of molten glass, means for enclosing the charges so severed, means for moving said enclosing means downwardly with said severed charges at a speed which is greater than the speed of the normal gravity fall of said charges, stationary means for opening said enclosing means as it approaches the limit of its downward movements and stationary means in the path of movement of said enclosing means for assisting the cushioning and reversal of its downward movements.

9. The combination of means including oppositely moving shear blades for periodically severing mold charges from a suspended stream of molten glass, means for enclosing the sides of the charges so severed, means for moving said enclosing means downwardly with said severed charges at a speed which is greater than the speed of the normal gravity fall thereof, stationary means for opening said enclosing means as it approaches the limit of its downward movement and spring means in the path of movement of said enclosing means for assisting the cushioning and reversal of its downward movements.
